[57] CLAIM

The ornamental design for a vehicle tire, as shown and described.

DESCRIPTION

FIG. 1 is a perspective view of a vehicle tire showing my new design, it being understood that the tread pattern is repeated uniformly throughout the circumference of the tire and the opposite side is the same as that shown;

FIG. 2 is a front elevation view thereof; and

FIG. 3 is a side elevation view thereof.

FIG. 1

FIG. 2

FIG. 3
